OPERATING AND LOCKING MEANS FOR
SLIDING CAR DOORS AND THE LIKE

Argyle Campbell, Chicago, Ill., assignor to Enterprise Railway Equipment Company, Chicago, Ill., a corporation of Illinois

Application June 23, 1933, Serial No. 677,229

4 Claims. (Cl. 268—44)

My invention relates to improvements in operating and locking means for sliding car doors and the like.

An object of my invention is to provide co-operating members on a sliding door and car structure such as will permit of the operation of a sliding door by means of a horizontally disposed removable bar in a manner as to permit of great leverage being exerted for initiating the opening movement of the door or for prying the door to fully closed position.

Another object of my invention is to so modify the usual securing hasp employed in connection with car doors so as to cooperate with a removable bar and fixed abutment on the car structure to move the door.

A more specific object of my invention is to combine in one mechanism the usual door hasp with a door starter and opener in such a manner as to dispose the prying portions in alignment with the hasp and sealing means. In house cars and the like having a sliding door it is usual to provide a hasp on the door in combination with keeper means on the car structure for retaining the door in closed position and it is also the practice to provide independent of the said hasp a door starter and opener for moving the door to either open or closed position. The hasp and door starter are usually separated from each other vertically and, due to the intervening space, it is oftentimes difficult to bring the hasp into engagement with the keeper, and I overcome such difficulty by making provision for prying the doors at a location in alignment with the hasp. The combining of the sealing and operating means in one mechanism also is conducive to a reduction in weight and makes for economy.

For further comprehension of my invention reference is made to the accompanying drawings, 40 wherein:

Fig. 1 is a side elevational view of a part of car side and door having my improvements applied thereto;

Fig. 2 is a sectional plan view on an enlarged scale of a portion of Fig. 1 taken on a line 2—2 of said Fig. 1; and

Fig. 3 illustrates on an enlarged scale a vertical elevational view of the hasp and mounting therefor, as illustrated in Fig. 2.

50 My improvements are shown as applied to a box or house car having a sliding door mounted on anti-friction rollers adjacent the bottom of the door.

In the drawings 10 indicates the body of the 55 car including side walls 11, side sills 12, front

door post 13, said door posts being provided adjacent the front marginal edge of the door with a sealing member 14. The door A is shown as including a main body plate 15 and provided at the lower part thereof with roller brackets 16 having rollers 17 mounted upon a track 18, the latter being supported at the bottom of the door opening. The door A adjacent its front margin is provided with a front marginal reinforcing member 19 preferably formed of Z-shape having web 10 20 extending transversely of the door. The respective flanges indicated at 21 and 22 are respectively disposed in the inner and outer plane of the door. The inner flange 21 is adapted to extend within and register with the sealing member 14, and the outer flange 22 is disposed in overlying relation with and secured to the body plate 15 of the door.

My improved construction includes a bracket B disposed on the car structure beyond the front edge of the door, and a hasp-like member C pivotally mounted on the door on a bracket D. The hasp member extends into cooperating relation with the bracket D and is locked relatively thereto by a sliding retainer member E. The bracket 20 B is provided with a base portion 23 riveted or otherwise secured to the car structure. In the case of double doors being employed it will be understood that such member B would be mounted on one of the doors instead of on the 30 car structure. Outstanding from the base portion 23 is a body portion 24 which is formed at its outer end with upper and lower elongated vertical extending portions 25 and 26 respectively. The said portions are spaced from each other 35 vertically an appreciable distance to provide a recess 27 intermediate said projections, and said portions 25 and 26 have a vertically extending T-shape slot 28 formed therein. The body portion 24 is spaced lengthwise an appreciable distance from the outer edge of the door, and intermediate the said body portion and door there is disposed an integral bracket portion 29 which extends lengthwise of the car in alignment with the recess 27; said bracket portion 29 is provided 45 with two pockets 30—30, said pockets being spaced from each other in the direction of movement of the door and preferably disposed in the same horizontal plane. Rearwardly of the pockets there is an integral bracket portion 31 adapted 50 to brace the said portion 29 relatively of the portion 24.

The hasp-like member C is of an elongated form and is pivotally mounted at one end on a pivot 32, the latter being carried by the bracket D. 55

The hasp is adapted to be extended lengthwise of the door into overlying relation with respect to the pockets 30, and the end 33 of the hasp opposite to the pivot is shaped to fit within the recess 5 27 of bracket B; said portion 33 is formed with a T-shaped vertical slot 34 corresponding in shape to the shape of slot 28. The respective slots 28 and 34 are adapted when the parts are in operative relation to register in order to have the retaining member E extended through the slots of 10 both members, the said retainer being likewise formed of corresponding shape.

Intermediate its pivotal mounting and the end 15 33, the member C is formed with two openings 35—35, said openings being located in substantially the same horizontal plane as the pockets 30. The openings 35 are flared in opposite directions as indicated at 36 and the opening through which the pivot 32 extends is likewise flared as indicated at 37, the latter being for the purpose of 20 providing a loose connection to allow the member C to have lateral movement and swing outwardly as well as in a plane parallel to the plane of movement of the door. The bracket member D is provided with a base portion 38 riveted or 25 otherwise secured to the door structure, and outstanding from said base portion are walls 39 and 40 which cooperate with an outer wall 41 to form a housing in which the pivotal end of member B 30 is extended and confined, said respective walls 39 and 41 providing a support for the pin 32.

That portion of the retainer E which is slidably mounted in the member B is provided with a slotted opening 42 through which a rivet 43 extends 35 to maintain the parts in assembled relation. The lower portion of the retainer is provided with an opening 44 adapted to register with a correspondingly formed opening on the member B, for the accommodation of a car seal.

40 The operation of the device is as follows:

Assuming the hasp to be in operative locked position as indicated in Fig. 2, to open the door the operator first effects disengagement between the retainer E and the hasp B and the latter is 45 then swung outwardly to the position indicated by conventional dotted lines. A removable bar F is then inserted through one of the openings 35 and into one of the pockets 30, the extreme end of the bar being confined by the pocket 30 to 50 provide a fulcrum for the bar. Pressure is then exerted on the opposite end of the bar in a direction to open the door. During the turning movement of the bar the loose pivotal mounting of the hasp allows a certain amount of lateral movement 55 of the hasp, and the flared openings 36 in turn compensate for relative movement between the hasp and bar brought about by the movement of the door. Should an extended movement of the door be desired, the end of the bar is moved into 60 the next successive pocket.

The closing of the door is a reverse operation to the above described. The operator engages one of the pockets with the end of the bar and if further movement is desired the end of the bar is transferred to the adjacent pocket and closure 65 of the door effected. With the door in open position, the hasp swings downwardly in a plane parallel to the plane of the door and assumes the position as indicated by the dotted lines in Fig. 1, in 70 which position it is out of the path of the discharge opening.

I claim:

1. In a railway car, the combination with adjacent door members, one of which is slidably mounted relatively to the other; of a keeper carried by one of said members, a hasp carried by the other of said members; said hasp when in operative relation extending beyond the edge of the door for cooperation with the keeper for retaining the door in closed position; and cooperating abutment means on the hasp and keeper adapted to receive an end of a removable bar for moving the door by a movement of the bar, said respective abutment means being disposed in alignment and in overlying relation to each other to permit of operation with the bar in a substantially horizontal plane.

2. In a railway car, the combination with adjacent door members, one of which is slidably mounted relatively to the other; of a hasp member pivotally mounted on the slidable door member for universal movement; a hasp keeper mounted on the other door member and having a socket portion adapted to accommodate the outer end of the hasp; a retainer slidably mounted on the keeper and adapted to engage with the hasp to retain the latter in fixed relation to the keeper, said keeper being spaced lengthwise from the end of the door, said keeper and hasp intermediate the retainer and the door member being provided with cooperating abutments adapted to receive the end of a removable bar for moving the slidable door member by a movement of the bar.

3. In a railway car, the combination with adjacent door members, one of which is slidably mounted relatively to the other; of a hasp keeper mounted on one of said door members and including a bracket having a pair of outstanding lugs extending outwardly therefrom and spaced from each other vertically; a reciprocable retainer mounted in the said lugs; a hasp carried by the other of said door members, said hasp being pivotally mounted with respect to its associated door member and having an elongated body portion adapted to be positioned between the lugs of the keeper, said hasp being provided with a vertical extending opening through which the hasp retainer is adapted to extend for locking the door members in fixed relation to each other; and an abutment means on the hasp and keeper respectively, adapted to receive a removable bar for moving the door by means of the bar.

4. In a railway car, the combination with adjacent door members, one of which is slidably mounted relatively to the other; of means for inducing relative movement between said members and locking said members in fixed relation to each other, said means including abutments carried by the respective door members, one of said abutments being carried by one of the door members and presenting an open-ended pocket adapted to receive one end of a movable bar, and the other of said abutments presenting a pocket disposed in substantial alignment of the opening, said respective pockets and opening being adapted to accommodate a removable actuating tool positioned to swing in a plane substantially at right angle to the plane of movement of the door member; and sealing means cooperating with the said members for locking the door and the associated car members in fixed relation to each other.

ARGYLE CAMPBELL.
